UNITED STATES PATENT OFFICE.

HENRY C. THOMSON, OF WEST ROXBURY, MASSACHUSETTS.

GUIDE CARD FOR CARD INDEXES.

Application filed March 7, 1921. Serial No. 450,315.

To all whom it may concern:

Be it known that I, HENRY C. THOMSON, a citizen of the United States of America, residing at West Roxbury, in the county of 5 Suffolk and State of Massachusetts, have invented new and useful Improvements in Guide Cards for Card Indexes, of which the following is a specification.

My invention relates to the guide or division cards commonly employed in card indexes to separate or divide the card units of which the index is made, up into distinct groups or classifications.

So far as I am at present informed, the 15 guide card hitherto employed has had the following characteristics. It has commonly included a main or body portion which is of substantially the same width and height as that of the card units with which it is associated, except that for a portion of its 20 breadth the height is somewhat increased so as to provide a small area, called the tab. Thus the tab is supported by the main body of the guide card, so as to project above the 25 main body of the card units; and upon said tab is carried in visible and easily legible position raised above the top surface of the index, the matter or indicia which serves to characterize the cards grouped under said 30 guide card.

Having noticed that the type of guide card just described requires for its manufacture a superficial area of material which is in excess of the area of the card units by 35 the area of the tab, it has occurred to me that the primary functions of the body of the guide card in separating the cards at the desired division point, and of supporting and locating the tab could be performed by 40 a card the area of whose body was very materially less than that of the card unit. In short, that there is a large proportion of the superficial area of the guide card which is wastage so far as its functional importance 45 is concerned.

One object of my invention is to devise a guide card for card indexes or the like which is of an improved type and of a novel shape or outline, and which is designed to secure 50 the result that the area of the guide card which has the functions of separating the groups of cards and of supporting and locating the tab shall be materially reduced as compared with the cards of the prior types; 55 thus eliminating the wastage above referred to.

Another object of my invention is to reduce the breakage, commonly experienced in index cards of the prior types, along the line where the tab joins the body of the 60 card. In such prior types, the body of the guide card, being of full width for its entire height, has little or no capacity for bending as pressure is applied upon the tab in the course of fingering the guide cards. 65 The consequence is that the tab tends to bend at its line of junction with the body of the card and these repeated bendings in time cause the tab to break off.

In my improved guide card however the 70 tapering form of the portion of the card leading up and supporting the tab and the gradual reduction in its width from the base to the tab results in the partial bending or 75 yielding of this portion of the card as pressure is applied to the tab, and such yielding prevents the bending effect of pressure exerted upon the tab becoming so localized at the base of the tab portion as to result in the 80 breaking off of the same.

At the same time the improved guide card forming the subject of my invention is designed to embody all the functions, utilities, and advantages possessed by the guide cards 85 of the prior type hitherto employed.

Referring to the drawings:

Fig. 1 shows an index card embodying my invention in one of its preferred forms.

Fig. 2 shows a blank piece from which the 90 card of Fig. 1 is cut in the process of manufacturing the same.

Fig. 3 shows an index card embodying my invention in a modified form.

Fig. 4 shows a blank from which the card of Fig. 3 is cut in the process of manufacturing the same. 95

Fig. 5 shows a set of index cards made up from the cards shown in Figs. 1 and 3 with one additional guide card.

Fig. 6 shows a further modification of an 100 index card embodying my invention.

Fig. 7 shows a blank from which the card shown in Fig. 6 is cut in the process of manufacturing the same.

Fig. 8 shows a still further modification of 105 an index card embodying my invention.

Fig. 9 shows a blank from which the card shown in Fig. 8 is cut in the process of manufacturing the same.

Referring to Fig. 1 of the drawings the 110 guide card has a base dimension 1 which is substantially identical with that of the cards

comprising the index with which it is employed. One lateral edge 2 (as shown in Fig. 1, the right hand edge) is substantially perpendicular to the base and extends to a height which exceeds that of the index cards (assumed in all the Figures to be indicated by the dotted line $x-x$) by the amount which it is desired to have the tab project above the cards of the index.

10 The top of tab edge 3 of the guide card lies substantially parallel to the base of the same, and has a length corresponding to the width desired for the tab. From the end of the tab edge which lies toward the center of the card 15 the other lateral edge (being the left-hand edge as shown in Fig. 1) is carried down diagonally to the left hand corner of the base of the card.

Thus the card has a general form which 20 is substantially that of a trapezoid, having its base and top, or tab, edges parallel but with its side edges sharply inclined or beveled with respect to the base and each other; the whole providing a relatively narrowed 25 top edge portion or tab projecting above the index cards (i. e. above the line $x-x$).

While in the case of the guide card shown in Fig. 1 and above described, the tab is located at the right side of the card, a reversal 30 of the card will cause the tab to be presented at the left side of the cards. Thus by the simple expedient of reversal, a card may be made to serve as a right or a left; according 35 as it is desired to locate the tab at one side or the other of the card index.

Where it is desired that the tab be located intermediate the ends of the guide card, I 40 employ a card of the type shown in Fig. 3. In this card, as before, the base and tab dimensions, respectively 5 and 6 and the height 45 of the guide card are determined by the size of the index cards and the amount of projection desired for the tab. Both lateral edges 7 and 8, however, are inclined or beveled with respect to the base so that the tab edge is located more or less toward the center of the card; the amount of the lateral displacement being determined by the 50 amount of the bevel or angular inclination of said edges relative to the base.

The process of forming guide cards of the types just herein before described by me is one which permits the cards to be formed without waste of material. In the preferred 55 mode of manufacture the cards are formed by cutting a strip of material, which has the height of the guide card, first into blanks having the form of rectangles or of rhomboids (according as cards respectively of 60 the types shown in Fig. 1 or Fig. 3 are to be formed) with a length equivalent to the combined lengths of the base and tab edges of 65 the guide card, and then severing said blanks along a line extending diagonally across the same and connecting points (9—9 in Fig. 2,

10—10 in Fig. 4) located on opposite sides of the blank and lying at distances from the adjacent corners of the blank, equal to the length of the tab edge. A single severance 70 of such a blank will provide without waste two guide cards of substantially identical form which complement each other in forming the blank from which they were cut.

In practice it becomes more economical to 75 carry on the manufacture of my cards by making the cuts forming the blanks from the strips of material and diagonally severing the blanks to form the guide cards or simultaneously by means of a suitable die or 80 by other cutting mechanisms well known to the art; but for clarity in explanation, the cards are in this application considered as manufactured in pairs from single previously formed blanks.

By combining guide cards of the type 85 shown in Figs. 1 and 3, in pairs individually reversed to form "rights" and "lefts," the tabs may be located at suitable intervals 90 successively from one side to the other of the top of the index, in the manner shown in Fig. 5, it being noted that the set of cards shown in Fig. 5 includes a guide card (as, e. g., the one with the tab marked "K—O") 95 with both side edges having the same angular inclination, and which supplies a center card for the set.

If desired to avoid the presence of sharp 100 corners at extremities of base edge of card, these corners may be trimmed off as along the dotted lines $y-y$, and $z-z$, as shown in Fig. 3; suitable allowances of course having 105 previously been made to secure the proper length of the base.

Guide cards embodying my invention may 110 also be made in the forms shown in Fig. 6. These cards, like those shown in Figs. 1 and 3, include the base edge 21 and the tab edge 23 lying substantially in parallelism. In the cards shown in Fig. 6 the right hand lateral edge 22 is perpendicular to the base 21, while the left hand lateral edge 24 is carried from the corner of the tab edge down to the left hand or adjacent corner of the card in a course which while not, as in the card of 115 Fig. 1, a straight line is substantially direct, although curving, as shown. Preferably the curve for such lateral edge 24 is so designed as to cut the rectangular blank from which the cards are cut (shown in Fig. 7) into two 120 halves of identical outline. As before, one of these halves may be employed in reversed position when it is desired to provide a card with the tab lying at the left hand of the index instead of at the right hand as shown 125 in Fig. 6.

Further by designing the said curved lateral edge 24 so that it meets the tab and base edges at substantially right angles, an 130 approximation to a rectangular form for the corners of the card where the curved

edge intersects the base can be secured, and also the angular inclination at the corner of the tab in the cards shown in Figs. 1 and 3 can be eliminated.

- 5 Both lateral edges 25 and 26 of the cards can be curved as is shown in Fig. 8, when it is desired to locate the tabs at lateral positions on the index intermediate the extreme ends.
- 10 Cards of the curved-edge types are manufactured in similar manner to those of the types shown in Figs. 1 and 3; the only difference being that the blanks from which the cards of Fig. 8 are cut have edges of curved form and that the severance cut of the blank is also curved instead of straight.

The advantages resulting from a guide card of the improved types just described reside in the consideration that the material required for my guide card is very appreciably less than for a guide card of the prior types; a fact that becomes manifestly apparent even by a casual comparison of the prior and my types of guide card.

25 Having thus described my invention, what I claim and desire to secure by Letters Patent is:—

1. Guide cards for card indexes and the like having a base edge and a tab edge lying substantially in parallelism, the tab edge being shorter than the base edge, and lateral edges forming the sides of said cards; the said guide cards being in pairs of substantially identical outline, in each of which pairs the one card complements the other when the two are placed with their lateral edges in contiguity and with the tab edge of one in linear alignment with and forming an extension of the base edge of the other, in covering in substantial entirety a surface whose longitudinal edges are parallel, and whose lateral edges are of substantially identical outline and lie in approximate parallelism with each other.

45 2. Guide cards for card indexes and the like having a base edge and a tab edge lying substantially in parallelism, the tab edge being shorter than the base edge, and lateral edges forming the sides of said cards; the said guide cards being in pairs of substantially identical outline in each of which pairs the one card complements the other, when the two are placed with their lateral edges in contiguity and with the tab edge of one in linear alignment with and forming an extension of the base edge of the other, in covering in substantial entirety a surface whose longitudinal edges are parallel, and whose lateral edges are of substantially identical outlines and lie in parallelism with each other; the individual cards of each pair being relatively reversed with respect to each other in said index so

that the tab of one card will lie to the right and the tab of the other card at the 65 left of its center.

3. A guide card set for card indexes and the like made up of one or more pairs of similarly shaped cards, each of which cards has a base edge, and a tab edge which is 70 shorter than the base edge and substantially parallel thereto, and lateral edges forming the sides of said card, said individual cards of each pair being adapted to complement each other, when the two are placed side by side with lateral edges in contiguity and with the tab edge of the one in linear alignment with and forming an extension of the base edge of the other, in covering in substantially entirety a surface 80 whose longer or longitudinal edges are parallel, and whose shorter or lateral edges are of substantially identical outline and lie in parallelism with each other.

4. A guide card for card indexes and the like which is substantially in the form of a trapezoid having a base edge approximately equal to that of the index cards, a top edge substantially parallel to the base and materially shorter than the same, and 90 an altitude sufficiently in excess of the height of index card to cause that portion of the guide card adjacent the top edge of the index card above such edge to present a surface serving as index tab. 95

5. A guide card set for card indexes and the like made up of cards which are substantially of trapezoidal form having a base approximately equal to that of the index card, a top edge substantially parallel to the base and shorter than the same, and an altitude sufficiently in excess of the height of the index card to cause that portion of the guide card adjacent the top edge of the index card above such edge to present a surface serving as an index tab; said top edges in the different cards of the set being located at varying positions intermediate the length of said card. 105

6. Guide cards for card indexes, each having a base portion substantially equal to the width of the card units comprising the index, each of said guide cards having one of its lateral edges inclined at an angle to the base, the inclination of the said edges with 115 respect to the base differing on the said guide cards whereby to laterally displace the upper or tab edges of the various guide cards with respect to each other.

In testimony whereof I affix my signature 120 in presence of two witnesses.

HENRY C. THOMSON.
